COMBINED COMB AND HAIR CURLER

Julius Wenter, New York, N. Y.

Application September 6, 1950, Serial No. 12,068

Term of patent 14 years

(Cl. D86—10)

To all whom it may concern:

Be it known that I, Julius Wenter, formerly a citizen of Panama and having declared my intention of becoming a citizen of the United States, residing at New York, county and State of New York, have invented a new, original, and ornamental Design for a Combined Comb and Hair Curler, of which the following is a specification, reference being had to the accompanying drawing, forming a part hereof, in which:

Fig. 1 is a side elevational view of a combined comb and hair curler, showing my new design;

Fig. 2 is a plan view; and

Fig. 3 an end view of Fig. 1.

I claim:

The ornamental design for a combined comb and hair curler, as shown.

JULIUS WENTER.
